DESIGN FOR AN UPRIGHT SOAP RECEPTACLE

Laura V. Anderson, Glendale, Calif.

Application May 4, 1942, Serial No. 106,787

Term of patent 14 years

To all whom it may concern:

Be it known that I, Laura V. Anderson, a citizen of the United States, residing at Glendale, in the county of Los Angeles and State of California, have invented a new, original, and ornamental Design for an Upright Soap Receptacle, of which the following is a specification, reference being had to the accompanying drawing, forming a part thereof.

In the accompanying drawing,

Fig. 1 is a perspective view of an upright soap receptacle embodying the features of my invention;

Fig. 2 is a top plan view of the upright soap receptacle;

Fig. 3 is a side elevational view of the upright soap receptacle; and

Fig. 4 is an end view of the upright soap receptacle.

I claim:

The ornamental design for an upright soap receptacle, as shown.

LAURA V. ANDERSON.
